UNITED STATES PATENT OFFICE

121,802

DESIGN FOR A BOTTLE

Samuel P. Benjamin, Jr., West Haven, Conn.,
assignor to Cosmetics Research Corporation,
New Haven, Conn.

Application December 28, 1939, Serial No. 89,180

Term of patent 3½ years

To all whom it may concern:

Be it known that I, Samuel P. Benjamin, Jr., a citizen of the United States, residing at West Haven, in the county of New Haven and State of Connecticut, have invented a new, original, and ornamental Design for a Bottle, of which the following is a specification, reference being had to the accompanying drawing, forming part thereof.

I claim:

The ornamental design for a bottle, as shown.

SAMUEL P. BENJAMIN, JR.
